UNITED STATES PATENT OFFICE.

JOHN COYLE, OF EVERSON, PENNSYLVANIA, ASSIGNOR OF ONE-HALF TO ABRAHAM COHEN, OF CONNELLSVILLE, PENNSYLVANIA.

PAPER-HANGING DEVICE.

Application filed February 20, 1925. Serial No. 10,630.

To all whom it may concern:

Be it known that I, JOHN COYLE, a citizen of the United States, residing at Everson, in the county of Fayette and State of Pennsylvania, have invented new and useful Improvements in Paper-Hanging Devices, of which the following is a specification.

This invention relates to paper hanging devices, and more particularly to a device 10 for supporting a strip of paper adjacent to a wall or ceiling of a room so as to permit ready application of the same.

One of the main objects of the invention is to provide a device of simple construction 15 and operation which, when not in use, may be readily folded so as to occupy a minimum of space and produce a compact bundle for transportation. A further object is to provide simple and efficient means for supporting 20 and holding the paper, this means including supporting and holding members which are independently detachable. Another object is to provide an attachment which may be readily applied for suspending 25 a strip of paper by one edge in vertical position so as to be applied to a wall of a room. Further objects will appear from the detailed description.

In the drawings:—

30 Figure 1 is a plan view of a device constructed in accordance with my invention;

Figure 2 is a side view of the same;

Figure 3 is a detail perspective view of the means for securing the upper supporting 35 arms;

Figure 4 is a detail of one of the paper holding clamps;

Figure 5 is a perspective view of the device used to hang a border;

40 Figure 6 is a perspective view of the device used to hang paper on a side wall.

The device is provided with a standard 1 composed of a plurality of sections 2, 3 and 4 which are slidably connected by keepers 5 and can be secured in adjusted relation by cam levers 6 carried by straps 7 secured to the upper end portions of members 2 and 4. A suitable supporting base 8 is secured upon the lower end of member 2 to hold the device in operative position, and is provided with four feet 8^a mounted on casters 8^b.

45 A sleeve 9 is slidable on member 4 and is adjustable by means of a cam lever 10 which is mounted between a pair of ears 11 50 projecting from this member. This

sleeve is provided at each side with two tabs 12 having eyes 13 which are adapted to receive the bight portions of the lower ends of downwardly converging brace arms or bails 14. The upper ends of arms 14 60 are bent outwardly to provide pins 15 which fit through any one, selectively, of a series of openings 16^a in arms 16 the inner ends of which are pivotally secured by pins 17 between ears 18 extending from the lateral faces of a collar 19 fitting about the upper end portion of member 4 and secured thereon in any suitable or preferred manner. This provides simple and efficient means for supporting rollers 20 which are mounted between the outer ends of arms 16, these rollers being positioned at opposite sides of the standard. At each end of each roller 20 is provided a spring clamp 21 the jaws of which are directed downwardly to releasably secure the edge portion of a strip of paper supported thereby in vertical position 75

When using the device for papering ceilings, a strip of paper to which paste has been applied is placed upon the rollers 20 as indicated in Figs. 1 and 2, the standard 1 being partially telescoped to bring the rollers into position to permit the paper to be easily placed thereon. The standard is then ex- 80 tended so as to bring rollers 20 into position adjacent the ceiling and the device is moved on casters 8^b into position to properly match the strip of paper with the adjacent side of the ceiling or with a strip previously applied. The portion of the strip between 85

rollers 20 is then brushed onto the ceiling so as to adhere thereto after which the end portions of the strip are brushed out. If desired, after the strip of paper has been properly matched with a strip previously applied, upper section 4 of standard 1 may be raised slightly so as to cause rollers 20 to press the paper firmly against the ceiling, after which the device may be moved along the floor in one direction to cause the 90

rollers to press the central portion and one end of the paper strip against the ceiling, the device being then moved in the opposite direction to roll out the other end portion of the strip. In this manner, the paper can be quickly and easily applied to the ceiling. Ordinarily, the end portions of the paper strip which depend from the rollers will act to hold the paper between the rollers straight and without any sag. In using 105

a short strip, the portion between the rollers can be held against sagging by securing the edge portions of the paper by means of clamps 21 which can be opened by cords 23 5 after the central portion of the strip has been applied. By changing the positions of pins 15 of arms 14 in openings 16^a of arms 16, the rollers 20 can be raised or lowered to accommodate strips of paper of different 10 lengths. This adjustment of the rollers also adapts the device for use in connection with rooms having either unusually high ceilings or very low ceilings.

In using the device for applying borders 15 it is positioned with rollers 20 at right angles to the side wall of the room, and the strip of paper is suspended from one edge by means of clamps 21, as indicated in Fig. 5, standard 1 being adjusted to position the 20 paper at the proper height. The portion of the paper between the clamps is then brushed onto the wall, after which the paper is released from the clamps and the end portions of the strip are brushed out. In applying 25 strips of paper vertically to side walls, one end of the paper is held between clamps 21 of one pair of arms 16 which are adjusted to position the upper end of the strip at the proper height, as indicated in Fig. 6. The 30 paper below the clamps is then brushed onto the wall, after which the paper is released from the clamps and the upper end of the strip is brushed onto the wall. When the device is used in this manner, the pair of 35 arms 16 not in use may be lowered into full inoperative position, as illustrated in Fig. 6, so as not to obstruct access to the strip of paper being applied.

By disengaging brace members 14 from 40 slots 13 of tabs 12, the pairs of arms 16 may be lowered into substantial parallelism with standard 1, which is then telescoped. When arms 16 are lowered and the standard is telescoped, the device occupies but little 45 space and can be readily carried by hand. This produces a very efficient and thorough-

ly practical device which has been found by experience to be of great practical value in paper hanging operations.

What I claim is:

1. In a device for hanging wall paper, a standard, paper receiving and supporting rollers positioned at opposite sides of the standard, and means for supporting the rollers and for detachably securing the same to the standard independently of each other. 50

2. In a device for hanging wall paper, a standard, paper receiving and supporting rollers positioned at opposite sides of the standard, and means for attaching the rollers to the standard so as to be supported thereby and for adjusting said rollers vertically independently of the standard. 60

3. In a device for hanging wall paper, a standard, paper receiving and supporting rollers positioned at opposite sides of the standard, arms supporting the rollers and pivoted at their inner ends to the standard, a sleeve adjustable on the standard, and brace arms pivoted at their upper ends to 65 said supporting arms and at their lower ends to the sleeve. 70

4. In a device for hanging wall paper, a standard, paper receiving and supporting rollers positioned at opposite sides of the standard, arms supporting the rollers and pivoted at their inner ends to the standard, a sleeve adjustable on the standard, and brace arms pivoted at their upper ends to 75 the supporting arms and having their lower ends pivotally and detachably secured to the sleeve. 80

5. In a device for hanging wall paper, a standard, a collar mounted on the standard, and two arms carried by said collar and projecting outwardly and laterally from the standard, said arms being provided with means for gripping the end of a strip at 85 points near the opposite edges thereof.

In testimony whereof I affix my signature.

JOHN COYLE.
